CLOSURE FOR VALVES OF BAGS

Axel Norvig, Brooklyn, Conn., assignor to St. Regis Paper Company, New York, N. Y., a corporation of New York

Application September 1, 1943, Serial No. 500,756

3 Claims. (Cl. 229—62.5)

This invention relates to valve bags, and has for its object to provide a valve which may be positively closed, with a minimum of difficulty and a maximum of certainty, after the bag has been filled. The invention is particularly applicable to a bag in which the valve is formed by omitting the paste from one of the inner flaps in making a pasted-end diamond folded bag, or a similar type of valve.

Valves of the type mentioned close sufficiently for many purposes, and have been used extensively, but there are many materials which it would be desirable to package in valve bags, but of which even the small leakage usual from such bags is objectionable. The purpose of the present invention is to add a valve-closing means that does not interfere with the usual valve-bag filling operation and which may be operated to form a secure closure by a very simple movement.

Details of the invention will appear as the description proceeds.

In the accompanying drawing, Fig. 1 is a sectional view through a valve of a bag embodying one form of the invention and showing it in its position prior to filling; Fig. 2 is like Fig. 1, but shows the valve after it has been closed; Fig. 3 is similar to Fig. 1, but shows a modified embodiment of the invention, and Fig. 4 is like Fig. 3, but shows the valve after it has been closed.

In the form shown in Fig. 1 there is indicated a conventional type of valve bag having end-closing outer flaps 10 and 11 pasted together in the usual manner and inner flap 12 left free from paste to form a valve flap.

The addition which constitutes the present invention comprises a strip 13 extending from outside the bag through the valve opening and having its inner end folded back at 14 and adhered to the overlying flap 10 at 15. The folded back end of strip 13 also has securely fastened thereto a closure member which extends inward at 16 beyond the fold 14 of the strip, and is preferably stiffer than the strip.

It will be seen that a filling tube may be inserted beneath strip 13 with no difficulty, and that the strip and closure member 16 do not interfere in any way with the filling operation. When the bag has been filled and the filling tube withdrawn, strip 13 may be drawn out as shown in Fig. 2. This straightens the fold at 14 and folds the strip at 17 at the inner edge of where it is secured to flap 10. This swings closure member 16 outward beneath the inner end of flap 12, thereby securely closing the filling opening.

In the form shown in Figs. 3 and 4, the general construction is similar to that shown in Figs. 1 and 2, and the same reference characters are applied to identical parts. There is an additional sleeve 17' the inner end 16' of the upper wall of which forms the valve-closing member. If this sleeve is made of stiff paper or the like, it is creased at 18 so as to form a hinge for the member 16'. The sleeve may be secured in place by adhering it to the overlying flap 10 at 19 and to the underlying flap 12 at 20. The lower side of the sleeve terminates at 21 in position to be covered by member 16' when it is folded to closing position.

15 Strip 13' extends through the sleeve, is folded back at 14' and attached to the valve-closing member 16', and operates to fold that member to closing position, as will be readily understood from Fig. 4.

20 While, for simplicity of illustration, but one ply has been shown in the flaps formed from the bag walls, it will be understood that usually in practice several plies are employed in making the bags, and that the number of plies in the 25 bag wall has no direct bearing upon the supplemental closing arrangement illustrated. Also, it will be understood that it makes no difference whether the bag is gusseted or not. While I prefer to make pull member 13 or 13' of a flat 30 or ribbon like strip, it will be understood that any kind of a pull member may be used which will serve to swing the closure member into closing position, and any shaped closure member may be used which may be swung into position 35 to securely close the valve opening. Various other variations may be made in the construction, and any desirable and suitable materials may be used, and the parts may be secured together by sewing, stapling or the like instead 40 of, or in addition to, adhesive wherever desired or preferred. Other changes may be made in the details of construction within the terms of the appended claims while retaining the essential features of the invention.

45 What I claim is:

1. A valve type bag having a filling opening through the wall thereof, a valve flap extending into the bag from the inner side of the opening, an imperforate closure member secured 50 to the bag wall on the outer side of said opening and hinged with respect to the bag wall and having a free end extending into the bag further than said flap, and a thin flexible sheet strip pull member hingedly attached to the closure member with 55 the hinge line in spaced relation to said free end

thereof, said pull member extending outward through the filling opening to the exterior of the bag and operable to pull said closure member outward about its hinge to a position where it underlies the inner end of the valve flap to positively grip the latter against the pull strip.

2. A valve type bag having a filling opening through the wall thereof, a valve flap extending into the bag from the inner side of the opening, a closure member positioned adjacent said bag wall outwardly of the flap and having a free end extending into the bag further than said flap, a pull member comprising a thin flexible sheet strip one end of which is hingedly attached to the bag wall opposite to the flap and which has a portion extending from said attachment inwardly of the bag, the closure member being attached to such inwardly extending portion of the pull member in spaced relation to said free end, said closure member and attached inwardly extending portion hinging about said pull strip hinge and the latter operating to secure the closure member to the bag wall and the other end of the pull member extending outward through the filling opening and operable to pull said closure member to a position where it underlies the inner end of the valve flap, said closure member being a sheet of

material stiffer than the pull member where said pull member extends inwardly.

3. A valve type bag having a filling opening through the wall thereof, a normally flattened valve sleeve extending into the bag and secured in said opening, the upper wall of the sleeve having an inwardly projecting integral tab connected thereto along a hinge line, a closure means comprising a thin flexible sheet strip material, said strip operating as a pull strip and extending from outside the bag into and through said flattened sleeve along and substantially in the plane thereof to a reversing point, such pull strip being turned back upon itself at said point and said turned back portion being joined to the hinged tab on the inner end of said wall of said sleeve and which, before the valve is closed, normally protrudes from adjacent said reversing point generally inward of the bag beyond the other wall of the sleeve, the portions being constructed and arranged whereby upon pulling the strip outwardly in the sleeve, said tab is swung and pulled to an outwardly directed position and against the inner portion of the other lower wall of the sleeve, thereby acting to positively grip the latter sleeve wall against the pull strip.

AXEL NORVIG.
